UNITED STATES PATENT OFFICE.

ISAAC N. MYERS, OF LOS ANGELES, CALIFORNIA.

LIFE-SAVING DEVICE.

1,030,525.

Specification of Letters Patent. Patented June 25, 1912.

Application filed September 19, 1910. Serial No. 582,686.

To all whom it may concern:

Be it known that I, ISAAC N. MYERS, a citizen of the United States, residing at Los Angeles, in the county of Los Angeles and State of California, have invented new and useful Improvements in Life-Saving Devices, of which the following is a specification.

This invention relates to life saving devices or life buoys, and the object of the invention is to produce a buoy having a construction particularly adapting it to support the body in a horizontal position and providing means for enabling the hands and feet of the person lying upon the buoy to propel the buoy toward the shore.

In the annexed drawing forming a part of this specification, Figure 1 is a plan of the buoy constructed according to my invention. Fig. 2 is a side elevation, Fig. 3 is a rear elevation of the buoy. Fig. 4 is a cross section taken on the line 4—4 of Fig. 1 and particularly illustrating the propeller apparatus operated by the hands.

Referring more particularly to the parts, 5 represents the body of the buoy, which is in the form of a flat hollow plate of substantially rectangular form, at the side edges of which cigar shaped floats 6 are provided, the forward ends of the floats being slightly pointed and rounding upwardly. The plate 5 forms a rest for the body and near its forward end it is provided with two openings 7, through which the arms of the person lying on the rest may be thrust downwardly. Between the two holes 7, a block 8 is attached to the under side of the plate or rest by swivel bolt or pin 9, and the forward edge of this block is slightly pointed, as shown, so as to facilitate its passing through the water. This block is adapted to act like a rudder in order to steer the device as it advances through the water.

In the lower and rear portion of the block, a small shaft 10 is mounted, and the rear end of this shaft is provided with a propeller 11, which is adapted to be rotated by means of a crank shaft 12, which is disposed transversely of the block and provided with cranks 13, adapted to be rotated by the hands. This shaft 12 is provided with a bevel gear wheel 14, which meshes with a similar gear wheel 15 at the forward end of the shaft 10. It will be evident that

by reason of this construction, a person lying on the rest 5 may rotate the propeller 11, which will tend to advance the float through the water; at the same time by twisting the block on the swivel bolt 9 the device may be steered toward the right or left, as desired. The rear end of the plate 5 is extended so as to form a central rearwardly projecting tail or tongue 16, and this tongue is also hollow and assists in giving buoyance to the float. At the rear end of this tail and on the under side thereof, a guide 17 is formed which guides the slide block 18 in a front and rear direction; said slide block 18 is clamped in any position by means of a clamping screw 19. In this block a longitudinally disposed shaft 20 is provided, the rear end of which is provided with a propeller screw 21, and this shaft 20 is adapted to be driven by a crank shaft 22 mounted transversely in the block 23 and provided with cranks 24 having pedals 25, enabling the crank shaft to be rotated by the feet. The rear edge of the rest 5 is provided with recesses or concave edges or notches 26, which permit a free movement of the thighs in operating the device, it being understood that the body lies upon the float face downwardly.

In order to give greater security to the body, the forward part of the tail 18 near the rest 5 is provided with a bracket 27, which has a forwardly and upwardly projecting horn 28. This horn projects up over the rump of the person operating the device, so as to prevent the body from sliding toward the rear. In order to provide clearance for the clamping screw 19 the rear end of the tail is cut away on the under side so as to form a pocket 29, in which the clamping screw is located, as shown most clearly in Fig. 2. The tail 16 is of greater depth than the hollow plate 5 and is extended forwardly under the plate or rest 5 to about the point 29, where the tail terminates, as indicated in Fig. 2. The forward edges of the rest 5 are provided with concave pockets or notches 30, which are disposed about in alignment with the openings 7, and these notches form sockets for the arms, which may hang downwardly when the hand propeller is not being operated.

It should be understood that the hollow plate 5 and the floats 6 are formed of light

sheet metal, and form air-tight compartments, which give the device great buoyancy.

What I claim is:

- 5 1. A buoy consisting of a horizontal rest, a swivel block attached to the under side thereof, a propeller carried thereby, a crank shaft mounted in said swivel block, and means for actuating said propeller from 10 said crank shaft.
- 15 2. A buoy comprising a rest for the body having a tail extending rearwardly therefrom, a block mounted on said tail, means for adjusting said block in a front and rear direction, a propeller carried by said block, and foot pedals for actuating said propeller.
- 20 3. A buoy consisting of a buoyant rest for the body having elongated floats at the sides thereof having a centrally disposed rearwardly extending tail, and a horn near the rear edge of said rest and projecting forwardly over the rump of a body supported on the said rest.
- 25 4. A buoy consisting of a rest having elongated floats at the sides thereof, said rest having openings therethrough through which the arms may be thrust downwardly, a tail extending rearwardly from said 30 rest, an adjustable propeller near the rear end of said tail, and pedals for actuating said propeller by the feet.
- 35 5. A buoy consisting of a rest in the form of a hollow flat plate having openings there-

through, floats at the sides of said plate and 35 formed integral therewith, a propeller attached to said buoy on the under side of said plate, means for actuating said propeller disposed below said openings, a rearwardly extending tail, a propeller near the end of 40 said tail, pedals for actuating said last named propeller, and a bracket attached to said tail near said rest and having a horn projecting upwardly and adapted to project over the rump of the body lying on said rest. 45

6. A buoy comprising a hollow body rest, elongated floats secured thereto, a propelling means pivotally mounted near the front end of the device for guiding and assisting in the propelling thereof, and a propelling device at the rear end of the mechanism. 50

7. A buoy consisting of a hollow buoyant body support having side floats secured thereto, a hand operated propelling means having a pivotal engagement with the forward end of the buoy and adapted to guide its movement, and a longitudinal adjustable foot propelling means secured to the 60 rear end of the device.

In witness that I claim the foregoing I have hereunto subscribed my name this 10th day of September, 1910.

ISAAC N. MYERS.
